UNITED STATES PATENT OFFICE.

HARRY L. KATZ, OF BALTIMORE, MARYLAND.

REINFORCED CONCRETE CONSTRUCTION.

Application filed September 14, 1926. Serial No. 135,378.

This invention relates to reenforced concrete construction, and more specifically to reenforcing concrete beams, girders and slabs against diagonal tension or web shear, bond and tensile stresses.

Diagonal tension or web shear is an important factor in reenforced concrete design. In the present day practice, the shear and resultant diagonal stress are assumed to be carried by the concrete itself, by the longitudinal steel, and by vertical or inclined stirrups. The value of stirrups as diagonal tension reinforcement is questionable, and the results of experiments do not justify the amount of importance that has been given this method of reinforcement.

A second important factor is bond stress. Failure by slipping occurs where the shear and therefore the bond stress is greatest, namely at the supports. In practice, resistance to slipping, in addition to that inherent from bar friction and grip due to shrinkage of concrete, is ordinarily aided in various ways, as by utilizing stirrups and deformed bars, but this aid does not come into play until after the first slip. This latter difficulty to an extent has been variously overcome, as by forming the bars with hooked ends which are embedded in the concrete at the supports, or by extending the bars over the supports in the concrete a sufficient distance to secure anchorage by the bond stress there developed. Bar anchorage is frequently unsatisfactory, however, due to the development of secondary stresses which cause the beam to crack, with consequent failure.

A primary object is to provide adequate reenforcement by a simplified construction, whereby to obtain maximum strength with minimum expenditure of material.

Another object is to transmit the diagonal tension or web shear from the concrete to the web of a light weight steel beam, eliminating thereby the use of stirrups.

Still another object is to produce a mechanical anchor at the ends of the tension bars, thereby preventing secondary stresses in the beam which are usually due to bar anchorage, and eliminating slipping failure.

Other objects and attendant advantages associated with this invention will be later referred to or become apparent from the description following; and said invention may be briefly defined as consisting in the

novel features of construction, combinations and arrangements of parts hereinafter fully set forth and thereafter tersely stated by the subjoined claims.

In the further disclosure of the invention, reference is to be had to the accompanying sheets of explanatory drawings, constituting a part of this specification, and in which corresponding parts are distinguished by the same indices throughout the several views.

In the drawing, Figure 1 is a fragmentary plan view of a floor, the supporting columns appearing in section.

Figures 2 and 3 are vertical sectional views taken respectively on lines 2-2 and 3-3 of Fig. 1.

Figure 4 is an enlarged vertical section on line 4-4, Fig. 1.

Figure 5 is a vertical section on line 5-5, Fig. 4, and

Figure 6 is a similar enlarged view thru line 6-6, Fig. 1.

In the particular embodiment of the invention chosen for illustrating its characteristics, but which is not to be too conservatively regarded, the same embodies a concrete floor slab 10 supported by suitable columns 11, which may be in the form of H-column having web portions 8 and flange portions 9. Other types of conventional column sections may be utilized. The columns are fireproofed with concrete, as indicated at 7.

Depending from the floor slab between adjacent pairs of columns are girders 12 and beams 13. Similar intermediate beams 14 extend between the girders 12, as clearly shown in Figure 1. The beams or girders may be considered as T-beams, in which a portion of the slab acts as a flange. The neutral axis, indicated for illustrative purposes only at N-A (see Fig. 6), may be considered as slightly below the slab, tho, as well known, its location varies according to conditions. Tension members 15 of usual construction serve to reenforce the slab.

Referring to Fig. 6, numeral 16 designates a steel I-beam embedded in the concrete beam 14. The beam 16 is of light weight construction and preferably of the type illustrated in the U. S. patent to Lockheed, Number 1,554,108, issued Sept. 15, 1925. Light steel beams capable of functioning as in the instant case have only recently

been purchasable on the open market. It is important to note that the section 16 is positioned below the neutral axis, that is to say, in that portion of the concrete subjected to tension. Since concrete is strong in compression, it is unnecessary to reinforce the compression portion above the neutral axis. I am aware that it heretofore has been proposed to utilize I-sections in concrete beam reenforcing, but these sections are relatively large and heavy, and the upper portions of the steel are encased in the compression flange of the concrete, well above the neutral axis. The concrete beam is thus in effect split vertically in two, resulting in a less efficient structure. It will thus be seen that by positioning the beam 16 below the neutral axis, I avoid the aforesaid splitting of the beam, and obtain thereby important functions, both in economy of steel and efficiency of the concrete structure. Further, by using small light sections 16 so proportioned as to be below the neutral axis, the number of sizes of sections necessary to cover a wide variation in conditions is materially reduced, since by slight variation in raising or lowering of the steel beam, the strength of the concrete beam can be increased or decreased, all of which will be readily apparent to those conversant with the art.

As shown, the girders 12 and beams 13 are also provided with light steel sections 16. Reenforcements for the girders are preferably of twin formation, see Figs. 3 and 5.

The sections 16 are rigidly connected at their ends with the columns or beams they frame into, thru the instrumentality of angle brackets 17 and bolts or rivets 18, see Figs. 4 and 5. The column and beam connections are designed to carry the entire end reaction. Wind bracing (not shown) may be provided for wherever necessary or required, in the manner common to structural steel construction.

The function of the sections 16 is to transmit the diagonal tension or web shear from the concrete to the web 16' of the respective sections. Flange portions 16'' of the sections aid in resisting the tensile stresses. The use of stirrups and other shear carriers is thereby eliminated, and in eliminating these devices, it will be obvious that the members 16 function as shear members independently of the concrete.

Tension bars 20 and 21, which may be of any conventional shape, here shown as flat, are positioned as shown. Upper bars 20 may if desired be bent up as shown in Fig. 4, thereby aiding the steel beams in carrying stresses due to diagonal tension. The bars 20 and 21 have their terminal portions bent as shown and clamped between the angle brackets 17 and the adjacent column or beam support, see Figures 4 and 5,

the securing elements serving as a common securing means for both the bars and I-sections. It is of the greatest importance that the bars be securely anchored at the ends. By securing the bars to the beams and columns in the manner shown, the elastic limit of the steel may be reached without causing secondary stresses peculiar to the conventional methods of bar anchorage, thereby preventing shrinkage tension and developing the full tensile stress of the bars. Failure by slipping is avoided, thereby eliminating serious cracks at the tension side of the beam, namely at the points where shear and therefore the bond stress is the greatest.

It is to be noted the present construction utilizes steel columns in connection with the reenforced concrete construction. The fire-proofing 7 is not relied upon to carry the load on the columns, tho it assists and insures a stronger structure. By eliminating concrete and utilizing steel for the columns, I am enabled to avoid the conventional methods of bar anchorage, and employ my novel rigid connection, utilizing the steel support rather than concrete to prevent the bar ends from slipping. This is the safest and surest way.

Welding may be substituted for the rivets or bolts, and the ends of the tension bars may be secured at or near the supports in various ways, as by securing the same to the flanges of the sections 16 at their ends.

It will be apparent from the above that I have provided a very light, rigid steel skeleton frame designed to carry the entire dead load and forming a complete and independent steel structure which subsequently becomes reenforcement for the concrete, producing a rigid, fireproof, monolithic structure. It furnishes level supports for hanging the wood forms, avoids the necessity for shoring, and enables the steel to proceed independently and ahead of the concrete.

It will be further apparent that a monolithic skeleton reenforced concrete structure is provided in which provision is made for all the stresses and strains taking place, except those of direct compression, which of course, are taken care of by the concrete per se.

By the term "concrete" as herein used, I mean to include any fireproof cementitious material suitable for use in building purposes.

It is to be understood the invention is not limited to the construction shown, since various modifications may be made without departing from the spirit and scope of the appended claims.

I claim:

1. Reenforcements for a concrete beam comprising separate shear and tension members, said members embedded in said beam entirely below the neutral axis thereof, said

- shear member functioning independent of the concrete and said tension member anchored at its ends independent of the concrete, and means for supporting said beam.
- 5 2. The construction in claim 1, wherein said shear member comprises a relatively light weight longitudinal imperforate metallic beam.
3. The construction in claim 1, wherein 10 said shear member consists of a metallic beam of I-section in shape.
4. Reenforcements for a concrete floor beam, including a longitudinally extending metallic shear beam embedded in the concrete and functioning independently of tension reenforcement, said shear beam being positioned entirely below the neutral axis and functioning independent of the concrete, and means for supporting said beam.
- 15 20 5. A concrete beam having reenforcements therefor and a support, said reenforcements including a shear member and tension resisting means, said shear member being positioned entirely below the neutral axis and functioning independent of the concrete, and means connecting said shear member to said support.
6. A concrete beam having reenforcements therefor, steel supports, a shear member 30 functioning independent of the concrete, longitudinal tension bars, and means rigidly connecting terminal portions of said tension bars to said supports, to thereby provide a mechanical anchor functioning independent 35 of the concrete to eliminate slipping of the bars.
7. The construction in claim 6, wherein said shear member is entirely below the neutral axis.
8. In a reenforced concrete structure, a longitudinal tension member having end anchorage independent of concrete, and a separate longitudinal shear beam operative independent of the concrete, whereby the concrete is relieved of all shear carrying and end anchorage function, and means for supporting said structure.
9. The construction in claim 8, wherein the shear beam is positioned entirely below the neutral axis.
10. Reinforcement construction for concrete beams supported by steel columns, comprising a plurality of longitudinal tension members, said members having their ends vertically bent, means including brackets rigidly connecting said ends with said columns to thereby effect a mechanical bond independent of the concrete and whereby tensile stresses are transferred to the steel columns at said end connections, a longitudinal shear beam functional independent of the concrete, said connecting means also serving as common connecting means whereby the shear beam is secured at its ends to said columns, said connections being rigid and designed to carry the entire end reaction.
11. The construction in claim 10, wherein said shear beam is positioned entirely below the neutral axis.

HARRY L. KATZ.
